MOORE GOODFELLOW, OF COLUMBUS, OHIO, ASSIGNOR OF ONE-HALF
TO JOSEPH O. DYE, OF COLUMBUS, OHIO.

DELIVERY MECHANISM FOR BEET-HARVESTERS AND THE LIKE.

No. 833,456.

Specification of Letters Patent.

Patented Oct. 16, 1906.

Application filed February 24, 1906. Serial No. 302,777.

To all whom it may concern:

Be it known that I, MOORE GOODFELLOW, a citizen of the United States, residing at Columbus, in the county of Franklin and State of Ohio, have invented certain new and useful Improvements in Delivery Mechanism for Beet-Harvesters and the Like, of which the following is a specification, reference being had therein to the accompanying drawings.

This invention relates to delivery mechanism for beet-harvesters and the like, being designed, primarily, for use in connection with a beet-harvester such as is disclosed in another application filed by me of even date herewith, although the said delivery mechanism is applicable to other beet-harvesters and also to harvesters and diggers of other kinds. In machinery of this class where the beets or other vegetables are pulled or otherwise raised out of the ground it is sometimes desirable to deposit the vegetables upon the surface of the ground in a manner and location such as to facilitate their subsequent gathering into a wagon or other vehicle. In accomplishing this result it is desirable where the vegetables are grown in rows that the contents of two or more rows should be deposited or gathered together in a single row to facilitate the subsequent gathering thereof. It is also desirable where the machines employed are large and heavy and not adapted to make short turns that arrangements should be made whereby after the machine has traversed the field in one direction and finished harvesting one row the machine in making its return trip across the field may skip one or two rows adjacent to the row just finished, thereby avoiding the necessity of a short turn. When this is done, it is desirable that the delivery mechanism should not only operate to deliver the vegetables on either side of the machine, but also desirable that it should be capable of varying the distance from the machine at which the vegetables are deposited on the ground, so as to permit the contents of several rows to be deposited in a single row for subsequent gathering.

It is the object of my present invention to provide a delivery mechanism which shall meet these several conditions and which shall be capable of delivering the beets or other vegetables on either side of the machine at different distances therefrom.

Further objects of the invention are to provide a delivery mechanism of this character which shall be simple in construction, compact, so as to add but little to the size of the machine, which will work at a relatively low elevation, so as to prevent injury to the vegetables by dropping them from a height to the ground, which can be readily controlled by the driver from his seat, so that it may be stopped and started, driven in either direction, and readily adjusted to vary its discharge distance from the machine.

To these and other ends my present invention consists in certain novel features, which I will now proceed to describe and will then particularly point out in the claims.

In the accompanying drawings, Figure 1 is a side elevation of a machine embodying my invention in one form. Fig. 2 is a plan view of the same. Fig. 3 is a side elevation, on an enlarged scale, of the rear portion of the machine, showing so much thereof as relates more particularly to the delivery mechanism. Fig. 4 is a plan view, partly broken away, of what is shown in Fig. 3. Fig. 5 is a rear elevation of what is shown in Fig. 4. Fig. 6 is a front elevation of the movable frame of the delivery-conveyer detached, only a portion of the length thereof being shown. Fig. 7 is a similar view of the remainder of said movable frame. Fig. 8 is an enlarged transverse sectional view of said frame. Fig. 9 is a detail plan view showing one section of the conveyer proper detached. Fig. 10 is an elevation of the same. Fig. 11 is a detail sectional view illustrating in side elevation the mechanism for shifting and locking the movable frame. Fig. 12 is a rear elevation of what is shown in Fig. 11. Fig. 13 is a detail plan view, on an enlarged scale, of the gearing by which the conveyer is driven; and Fig. 14 is a vertical sectional view showing in side elevation what is shown in Fig. 13.

In the said drawings I have shown my invention as applied to a beet-harvester, such as is set forth in an application filed by me of even date herewith, the same comprising a main frame 1, composed of side members 2, which support bearings 3 for a rotating axle 4, driven by ground-wheels 5. This main frame supports pulling devices 6 and elevating devices 7, by means of which the beets are pulled from the ground, elevated, and discharged at the rear end of the main frame.

At said rear end of the main frame is located the delivery mechanism which I have devised and which I will now proceed to describe.

- 5 The main frame is provided at its rear end with two parallel transverse members 8 and 9, to which are secured three rearwardly-extending brackets, one indicated by the numeral 10, located at the middle of the main 10 frame, and the other two indicated by the reference-numerals 11 and 12, located at the sides of said main frame. The delivery mechanism comprises a frame 13, arranged transversely of the machine at the rear 15 thereof and supported on the brackets 10, 11, and 12 in such a way that it may be shifted in the direction of its length and transversely of the machine, so as to extend beyond the same on either side to any desired extent 20 within its range of adjustment. The construction of this movable frame which I prefer to employ is that shown more particularly in Figs. 6, 7, and 8. In this construction the frame comprises two inwardly-directed 25 angle-bars 14 and 15 at the top thereof and two outwardly directed angle-bars 16 and 17 at the bottom thereof, said angle-bars being connected by uprights 18 and said uprights being connected by diagonal braces 19. 30 Suitable cross-braces 20 (shown more particularly in Fig. 8) connect the front and rear sides of the frame thus formed. Some of the uprights 18 are extended above the upper angle-bars, as shown at 21, said upward 35 tensions being preferably outwardly inclined and being connected by guard-rails 22, so as to form guards on each side of the frame to hold the beets or other vegetables on the conveyor. 40 The movable frame 13 is supported on the brackets 10, 11, and 12, so as to slide lengthwise thereon, and the construction which I prefer for this purpose is that shown, in which the brackets 11 and 12 are provided 45 with supporting-rollers on which the frame travels. As shown, each of these brackets terminates at its rear end in an upright arm 23, which carries a flanged supporting-roller 24, on which the horizontal portion of the 50 angle-bar 16 travels. The arm 23 also supports a second roller 25, located above the horizontal flange of the angle-bar 16 and serving to prevent displacement of the frame in an upward direction. Each of the 55 supporting-brackets is further provided on the other or front side of the movable frame 13 with an upwardly-extending arm 26, which carries a roller 27. This roller 27 lies between the horizontal flange of the angle- 60 bar 17 on its under side and the similar horizontal flange of a second angle-bar 28, arranged above the said roller on the front of the frame 13. By reason of this construction vertical displacement of this side of 65 the frame is prevented. The arrangement

whereby the movable frame is provided with supporting-roller contacts both above and below is desirable by reason of the fact that when said frame is shifted outward, so that its projecting end overbalances the portion 70 thereof remaining on the other side of the supporting-rollers nearest the projecting end, the excess weight of the projecting end tends to move the inner end upward, so that the portion of the frame which is guided and supported by the rollers may either press upward or downward against the same, according to the position of the parts.

The movable frame 13, which carries the delivery-conveyer, hereinafter described, is 80 provided with means whereby it can be positively shifted in the direction of its length toward either side of the machine. This shifting mechanism comprises a suitable rack or its equivalent upon the frame and a pinion or toothed wheel engaging therewith and operated by the driver to shift the frame. In practice I prefer to employ for this purpose the construction shown, in which the rack is formed by means of a sprocket-chain 85 29, stretched between hooks or other suitable fastening devices 30, secured to the ends of the frame 13 at the front thereof. This sprocket-chain passes over a pinion, sprocket-wheel, or toothed wheel 31, carried by a 90 shaft 32, supported in a suitable bearing in a bracket 33, secured to the rear cross-piece 8 of the main frame. The shaft 32 is connected by a universal joint 34 to a forwardly-extending shaft 35, which latter extends forward to a point adjacent to the driver's seat and is there provided with an operating-crank 36. By this means it will be seen that the movable frame may be readily shifted in a horizontal plane transversely of the machine, so as to project from either side thereof to a greater or less extent, such shifting being readily accomplished by the operator from his seat. The movable frame 13 is also provided with means controlled by the driver 105 for locking it in different positions to which it may be adjusted. To that end the frame is provided on its front side with locking-plates 37, supported on the uprights 18 and having their front faces formed in forwardly- 110 converging inclines 38, having between them a notch 39 to receive the locking-bolt. This locking-bolt (indicated by the reference-numeral 40) is mounted in a suitable housing 41 in the upper end of the bracket 33, which 115 housing also incloses a spring 42, which acts to force the bolt rearward into engagement with the locking-plates.

43 indicates a chain or other suitable flexible connection connected to the forward end 120 of the locking-bolt 40 at one end, while its other end is connected to an arm 44, carried by a rock-shaft 45, controlled by a foot-lever 46 in front of the driver's seat. By means of this foot-lever the locking-bolt can be with- 125 130

drawn from engagement with the locking-
5 plates by the foot of the operator, leaving
his hand free to rotate the shaft 35 for the
purpose of adjusting the movable frame to
its desired position. The inclines 38 will
push back the locking-bolt 40 in case it is not
held back by the foot-lever, and the release of
10 said foot-lever will permit the locking-bolt to
engage with any desired one of the locking-
plates. These locking-plates are preferably
arranged at a distance apart equal to the dis-
15 tance between the rows of vegetables, so that
the discharge of the vegetables may be made
into one of the empty furrows already formed
by the operation of the pulling mechanism.

The movable frame, as already stated, sup-
ports the delivery-conveyer, which moves
horizontally in the direction of the length of
said frame. To this end the frame 13 is pro-
20 vided at each end with a transverse shaft 47,
each of said shafts having mounted thereon
near its ends two sprocket-wheels 48. The de-
livery-conveyer is composed of two sprocket-
25 chains 49, which pass around the wheels 48
and travel along the inwardly-directed hori-
zontal flanges of the angle-bars 14 and 15 of
the frame 13, which latter support them.
The conveyer comprises these sprocket-
30 chains 49, which are composed of links 50
and cross-pieces 51 in the form of flat strips
of metal riveted at their ends to lugs 52 on
the inner sides of the links 50. The con-
veyer thus constituted is sufficiently flexible
35 for its purpose, while at the same time firmly
supporting the vegetables, and sufficiently
open to permit any dirt which may become
detached from them to fall through onto the
ground. The conveyer thus constructed is
40 preferably driven by the mechanism which I
have shown for that purpose. It com-
prises a shaft 53, mounted in suitable bear-
ings on the central bracket 10 and on the
cross-pieces 8 and 9 of the main frame. This
45 shaft carries a pair of sprocket-wheels 54,
over which the sprocket-chains 49 pass, as
indicated in dotted lines in Fig. 5. In order
to hold the sprocket-chains in engagement
50 with the sprocket-wheels 54, I employ on
each side of each sprocket-wheel an idler 55,
under which the sprocket-chains 49 pass, as
also indicated in dotted lines in Fig. 5, thus
55 insuring the proper engagement of said
sprocket-chains with said sprocket-wheels
whatever the position of the movable frame
13 may be. The shaft 53 is driven in either
direction from the main axle of the machine,
and to this end there is mounted on said shaft
53, so as to rotate therewith and move longi-
tudinally thereon, a clutch member or sleeve
60 56. This clutch member or sleeve is shifted
longitudinally of the shaft 53 by means of a
lever 57, provided at one end with a yoke 58,
which engages a groove 59 in the central por-
65 tion of the clutch member 56. The lever 57
is pivoted at 60 upon a frame-piece 61, con-

necting the transverse members 8 and 9, and
has connected to its other end an operating-
rod 62, which extends forward and is con-
nected to a hand-lever 63 adjacent to the
driver's seat. This hand-lever is provided 70
with the usual locking quadrant, pawl, and
pawl-operating mechanism, so that by its
means the clutch member 56 may be moved
to and held in any one of the three positions
which it is adapted to assume. Coöperating 75
with the clutch member 56 there are mount-
ed loosely on the shaft 53 two bevel-pinions
64 and 65, located on opposite sides of the
clutch member 56. These bevel-pinions are
provided with clutch members to coöperate 80
with those of the member 56, so that when
the said clutch member is in engagement with
either one of said bevel-pinions the shaft 53
will be rotated in the direction of rotation of
said pinion. When the clutch member 56 is 85
in the central position, the shaft 53 is sta-
tionary, as the clutch member is out of en-
gagement with both pinions. The pinions
are driven in opposite directions by means of
a bevel-gear 66, mounted on a shaft 67, sup-
90 ported in bearings on frame members 68, con-
necting the cross-pieces 8 and 9. This shaft
67 has mounted thereon a sprocket-wheel 69,
which is driven from a sprocket-wheel 70 on
the main axle 4 by means of a sprocket-
95 chain 71 passing around both of the sprocket-
wheels 69 and 70. Incidentally in the par-
ticular construction illustrated the sprocket-
chain 71 also passes around a sprocket-wheel
72, by means of which a portion of the elevat-
100 ing mechanism is driven.

It will be understood from the foregoing
description that the delivery-conveyer may
be caused to move in such a direction as to
deposit the vegetables discharged thereon by
the elevator on either side of the machine at
105 will and that the point of deposit may be
regulated by the mechanism provided for
sliding the movable frame of the delivery-
conveyer in one direction or the other. 110
Thus the delivery mechanism meets the
conditions set forth in the opening para-
graph of the specification, enabling the ma-
chine to harvest in both directions, to skip
115 rows to avoid a short turn, and to pile the
vegetables from a plurality of rows in a sin-
gle row to facilitate their subsequent gather-
ing.

I do not wish to be understood as limiting
myself to the precise details of construction
hereinbefore described, and shown in the ac-
companying drawings, as it is obvious that
these details may be varied without departing
from the principle of my invention.

Having thus fully described my inven-
tion, what I claim as new, and desire to secure
by Letters Patent, is—

1. A delivery mechanism for harvesters of
the character described, comprising a de-
livery-conveyer arranged transversely with 130

respect to the machine and movable relatively thereto to vary the point of discharge on either side, means extending forward to the operator's seat for controlling such movement thereof, and means for actuating said conveyer in either direction, substantially as described.

2. A delivery mechanism for harvesters of the character described, comprising a delivery-conveyer arranged transversely with respect to the machine and movable in the direction of its length transversely of the machine to vary the point of discharge, means extending forward to the operator's seat for controlling such movement thereof, and means for actuating said conveyer in either direction, substantially as described.

3. A delivery mechanism for harvesters of the character described, comprising a delivery-conveyer arranged transversely with respect to the machine and movable in the direction of its length transversely of the machine to vary the point of discharge, means for positively so moving said conveyer, and means for actuating said conveyer in either direction, substantially as described.

4. A delivery mechanism for harvesters of the character described, comprising a delivery-conveyer arranged transversely with respect to the machine and movable in the direction of its length transversely of the machine to vary the point of discharge, means for positively so moving said conveyer, means for locking it in position after it is so moved, and means for actuating said conveyer in either direction, substantially as described.

5. A delivery mechanism for harvesters of the character described, comprising, in combination with a main harvester-frame provided with guiding and supporting means, of a delivery-conveyer comprising a frame arranged transversely with respect to the harvester-frame and movable relatively thereto in the direction of its length to vary the point of discharge, an endless flexible conveyer proper mounted on said movable frame longitudinally thereof, means carried by the main frame for driving said conveyer in either direction, and means supported near the operator's seat and connected to said driving means for controlling the direction of the movement thereof, substantially as described.

6. A delivery mechanism for harvesters of the character described, comprising, in combination with a main harvester-frame provided with guiding and supporting means, of a delivery-conveyer comprising a frame arranged transversely with respect to the harvester-frame and movable relatively thereto in the direction of its length to vary the point of discharge, means for positively so moving the same, an endless flexible conveyer proper mounted on said movable frame longitudi-

nally thereof, and means carried by the main frame for driving said conveyer in either direction, and for locking said conveyer-frame in adjusted position, substantially as described.

7. In a delivery mechanism for harvesters of the character described, the combination, with a main harvester-frame having rearwardly-extending brackets provided with guiding and supporting rollers, of a delivery-conveyer comprising a frame supported transversely with respect to the machine on said guiding and supporting rollers and movable thereon in the direction of its length to vary the point of discharge, said movable frame being provided with sprocket-wheels at its ends, a flexible conveyer passing around said sprocket-wheels, a shaft carried by one of the brackets and having sprocket-wheels to engage said flexible conveyer, and means for driving said last-mentioned shaft in either direction, substantially as described.

8. In a delivery mechanism for harvesters of the character described, the combination, with a main harvester-frame, of a delivery-conveyer comprising a frame arranged transversely with respect to the harvester-frame and movable in the direction of its length, shafts mounted at the ends of said movable frame and provided with sprocket-wheels near their ends, a flexible conveyer comprising sprocket-chains passing around said sprocket-wheels and transverse connecting members, a shaft supported from the main frame and extending under said conveyer, sprocket-wheels in said shaft over which the sprocket-chains pass, and idlers located above said sprocket-chains on opposite sides of said sprocket-wheels, substantially as described.

9. In a delivery mechanism for harvesters of the character described, the combination, with a main frame having a rotating axle, and a transverse shaft driven therefrom and provided with a bevel-gear, of a delivery-conveyer arranged transversely with respect to the machine and comprising a flexible conveyer proper having sprocket-chains, a longitudinal shaft carried by the harvester-frame and provided with sprocket-wheels to mesh with said sprocket-chains, said shaft having bevel-pinions loosely mounted thereon and meshing with opposite sides of the bevel-gear, a clutch member sliding on and rotating with said shaft between said bevel-pinions, a lever engaging said clutch member to shift the same, a controlling hand-lever, and a rod connecting said two levers, substantially as described.

10. In a delivery mechanism for harvesters of the character described, the combination, with a main harvester-frame, of a delivery-conveyer comprising a frame arranged transversely with respect to the harvester-frame and movable in the direction of its length, a

conveyer carried by said movable frame, a rack on said frame, a pinion on the main frame meshing with said rack, and a shaft connected with said pinion and extending forward to convenient reach of the operator, its forward end being provided with an operating-crank, substantially as described.

11. In a delivery mechanism for harvesters of the character described, the combination, 10 with a main harvester-frame, of a delivery-conveyer comprising a frame arranged transversely with respect to the harvester-frame and movable in the direction of its length, a conveyer carried by said movable frame, a 15 rack on said frame, a pinion on the main frame meshing with said rack, and a shaft connected with said pinion and extending forward to convenient reach of the operator, its forward end being provided with an operating-crank, said rack consisting of a 20 sprocket-chain stretched between the ends of the movable frame and said pinion consisting of a

sprocket-wheel meshing therewith, substantially as described.

12. In a delivery mechanism for harvesters 25 of the character described, the combination, with the main frame of the harvester, of a delivery-conveyer comprising a frame arranged transversely with respect to the machine and movable in the direction of its length, locking-plates arranged at predetermined intervals on said frame, a spring-actuated locking-bolt adapted to engage said locking-plates, a foot-lever arranged within convenient reach of the operator, and a flexible connection between said foot-lever and locking-bolt, 30 substantially as described.

In testimony whereof I affix my signature in presence of two witnesses.

MOORE GOODFELLOW.
